UNITED STATES PATENT OFFICE.

CHARLES F. KETTERING, OF DAYTON, OHIO, ASSIGNOR TO THE DAYTON ENGINEERING LABORATORIES COMPANY, A CORPORATION OF OHIO.

IGNITION SYSTEM.

1,401,479.

Specification of Letters Patent. Patented Dec. 27, 1921.

Application filed December 15, 1917. Serial No. 207,220.

To all whom it may concern:

Be it known that I, CHARLES F. KETTERING, a citizen of the United States of America, residing at Dayton, in the county of 5 Montgomery and State of Ohio, have invented certain new and useful Improvements in Ignition Systems, of which the following is a full, clear, and exact description.

This invention relates to improvements in 10 high-speed ignition systems for internal-combustion engines, and has for its object the provision of improvements in the high-speed ignition apparatus generally, and particularly of the kind covered by my Patent No. 15 1,272,056, issued July 9, 1918.

Further objects and advantages of the present invention will be apparent from the following description, reference being had 20 to the accompanying drawing, wherein a preferred embodiment of the present invention is clearly shown.

In the drawing:—

Figure 1 is a vertical sectional view of 25 the distributor unit embodying the present invention, certain of the operative parts being shown in elevation to show more clearly the relative arrangement of certain of the parts;

Fig. 2 is a view on an enlarged scale of 30 the engine driven member E, and coöperating parts shown centrally located in Fig. 1. That part of Fig. 2 to the left of the heavy line shows the parts in elevation, while the part to the right of the heavy line shows a 35 longitudinal sectional view of the member E and coöperating parts; and

Fig. 3 is a fragmentary top view of the distributor shown in Fig. 1, the top cover plate being removed to show the timer. Accompanying Fig. 3 is a wiring diagram 40 showing the primary and secondary circuits and diagrammatic plan views of the distributors.

Referring to the drawing, the distributor 45 unit forming a part of the ignition system embodied in the present invention, consists chiefly of a suitably formed hollow casing A, supporting at opposite sides distributors B and C, at the top of the timer D, and a 50 centrally disposed engine driven member E.

The member E consists of sections 10, 11 and 12, operatively connected in a manner to be described, the intermediate section 11 being supported in ball bearing 13, carried 55 by the lower end of casing A. Upper end

section 12 is supported in ball bearing 14, located in the bottom 15 of timer casing 16, which casing is nested in an annular recess formed in the top casing A.

The lower end section 10 of member E is shown broken away in Fig. 2, but in fact one end of section 10 is arranged to be connected to some moving part of the engine, not shown, for instance to the engine crank shaft by suitable gearing, and in a manner readily understood by those skilled in the art. From the upper end 17 of section 10 extends a longitudinal groove 18. The grooved end of section 10 extends loosely into the lower end of hollow section 11, in which is formed the curved slot 19. A grooved sleeve 20 is slidably mounted upon section 11, and a pin extends diametrically across sleeve 20, passing through slots 18 and 19. It will be seen that pin 21 serves as a connection between parts 10, 11 and 20, whereby said parts may rotate together. Any sliding movement of collar 20 will cause relative rotary movement between sections 10 and 11. The sliding movement of collar 20 is effected by means of a yoke lever 22, pivoted at 23 upon the frame A. The arm of lever 22, opposite sleeve 20, extends to some point outside the frame where it is connected in the well known manner to an operating lever located at the steering wheel. A stop 70, secured to the casing A, limits the movement of lever 22. 75

The lower end of section 12, which is bored out a certain distance, telescopes within section 11, and is formed with a curved slot 24 in alinement with a straight slot 25, formed near the upper end of section 11. Pin 26, passing through slots 24 and 25, serves to connect sections 11 and 12, 80 and it will be seen that any movement of pin 26, axially of member E, will produce relative rotation of sections 11 and 12. The aforesaid movement of pin 26 is effected by means of links 27, pivoted at their lower 85 ends to weighted ring 28, which is pivoted upon pin 29, passing through section 11, said links 27 being connected at their upper ends, each to the opposite ends of pin 26. The mass of weighted ring 28 is so distributed that as the speed of rotation of member E increases, said ring will tend to assume an approximately horizontal position, causing links 27 and pin 26 to move 90 upwardly. As the speed of member E falls 105

off, gravity will cause ring 28 to recede from the horizontal, and consequently pin 26 will be drawn downwardly.

Section 12 carries spiral gear 30, and at its upper end, timer cam 31, made of insulating material and adjustably held in position on section 12 by means of nut 32. Cam 31 is provided with three lobes, located 120 degrees apart, which are adapted alternately to contact with contact arms 33 and 34, pivotally mounted upon but insulated from timer casing 16. Arms 33 and 34 carry contacts 35 and 36, respectively, which contact respectively with stationary contacts 37 and 38, which are mounted on blocks 39 and 40 respectively. Springs 41 and 42 serve to urge arms 33 and 34 toward blocks 39 and 40 and thereby to maintain in contact the contacts 35, 37 and 36, 38 respectively. Springs 41 and 42 serve also as electrical connections between arms 33 and 34, and the binding posts 43 and 44 respectively.

By reference to Fig. 3, showing diagrammatically the use of this invention in connection with a 12-cylinder four cycle engine of the Packard type, a well known make of motor car, will be seen a source of current 45 having electrical connections 47 and 48, with blocks 39 and 40, respectively, and connections with primary windings 49 and 50 of separate induction coils. Conductors 51 and 52 connect primary coils 49 and 50 with binding posts 43 and 44 respectively.

Thus are provided two separate primary circuits through the timer device D, each circuit having co-operating contacts which are opened and closed by a common operating cam 31. The shaft E revolves at engine speed, and during the engine cycle of two revolutions, it will be seen that each primary circuit will be broken six times, and that there will be twelve breaks during each engine cycle, the breaks occurring alternately in the two circuits. Consequently sparking impulses will be induced in the secondary induction coil windings 53 and 54 alternately, and will pass alternately to center contacts 55 and 56 of distributors B and C respectively.

The distributors are of a well known construction, distributor B consisting of a rotating distributing arm 57, receiving current from center contact 55, and distributing it in recurrent sequence to stationary contacts 59, 60, 61, 62, 63 and 64, and distributor C consisting of distributor arm 58, receiving current from center contact 56 and distributing it in like manner, to stationary contacts 59', 60', 61', 62', 63' and 64'. The stationary contacts are connected to spark plugs of the proper cylinders, where, when a contact is made in one of the distributors, and a sparking impulse created in the secondary circuit by a break in the primary

circuit, this impulse will pass to the spark plug, and produce a spark across the plug points. The secondary coils are grounded on the frame, and thus the secondary circuits are completed. The stationary contacts of the two distributors are arranged in staggered relation as shown in the wiring diagram in Fig. 3, while the arms 57 and 58 are arranged to rotate in alinement; thus the arms function alternately in recurrent sequence and in unison with the breaking of the primary circuits, by cam 31 contacting with arms 33 and 34, respectively.

Since cam 31 rotates at engine speed to make twelve circuit breaks per engine cycle, and the two distributors together must distribute sparking impulses to twelve different spark plugs per engine cycle, the distributor arms should rotate at one-half engine speed in the particular embodiment shown.

As means for rotating the arms 57 and 58, there is provided a shaft 65 upon the opposite ends of which said arms are secured by set screws 66. Upon shaft 65 and in mesh with spiral gear 30 is a spiral gear 67, the gearing being so designed that the speed ratio of shaft 65 and the engine driven member E is 1:2. Shaft 65 is supported by ball bearings 68 and 69, carried by casing A.

From the foregoing description, it will be noted that there has been provided an ignition system for a high speed multi-cylinder combustion engine employing a plurality of primary and a plurality of secondary circuits, an engine driven timing device and distributors so arranged that sparking impulses will be created and distributed alternately to ignite the charges in the various cylinders, one induction system being at rest and recuperating, while the other system is at work; and that there has been provided in combination with said system manually operable means and automatic means, each capable of adjusting the time relation of the cycle of operations of the timer and distributors to the engine cycle concurrently, and each of said means capable of making adjustments independently of the other, but capable of effecting a joint control of the timer and distributor.

While the form of mechanism herein shown and described constitutes a preferred form of embodiment of the invention, it is to be understood that other forms might be adopted, all coming within the scope of the claims which follow.

What I claim is as follows:

1. In an ignition system for internal-combustion engines, the combination with a timing device and an engine driven member for operating the same; of a distributing device including a movable element; a shaft carrying the movable element; gearing between the engine driven member and

the shaft; and manually operable means and automatic means each for simultaneously adjusting the operation of the timing and distributing devices with respect to the engine, and each of the said means being capable of making adjustments independently of the other, but effecting a joint control of the timing and distributing devices.

2. In an ignition system for internal-combustion engines, the combination with primary and secondary circuits, a timing device including coöperating contacts in said primary circuits, distributing devices in the secondary circuits including distributor operating members, an engine driven shaft member having provisions for opening and closing the contacts in the primary circuit; of a second shaft transverse to the first mentioned shaft, carrying the said distributor operating members; gearing for imparting motion from the first shaft to the second shaft; and manually operable means and automatic means operably connected with the first shaft, each for simultaneously adjusting the operation of the timing and distributing devices with respect to the engine, and each of the said means being capable of making adjustments independently of the other but effecting a joint control of the timing and distributing devices.

3. In an ignition system for internal-combustion engines, the combination with primary and secondary circuits; of timing means for breaking and making the primary circuits including coöperating contacts and a cam coöperating therewith; distributing devices positioned on opposite sides of the timing means, each including stationary contacts and a rotor; an engine driven shaft carrying the said cam and a driving gear; a shaft carrying the distributor rotors and a driven gear meshing with the driving gear; and manually operable means and automatic means operably connected with the engine driven shaft, each for simultaneously adjusting the operation of the timing and distributing devices with respect to the engine, and each of said means being capable of making adjustments independently of the other but effecting a joint control of the timing and distributing devices, the control of the distributing devices taking place through the aforesaid gears.

4. In an ignition system for internal-combustion engines, the combination with a timing device including coöperating contacts in a primary circuit, and a cam member; of a distributing device including a rotor and stationary contacts in a secondary circuit; an engine driven member comprising coöperating shaft sections, one of the sections carrying aforesaid cam and a driving gear; a second shaft carrying the distributor rotor and driven gear meshing with the driving gear; and manually operable

means and automatic means operably connected with certain of the coöperating shaft sections of the engine driven member, each means for simultaneously adjusting the operation of the timing and distributing devices with respect to the engine, and each of said means being capable of making adjustments independently of the other but effecting a joint control of the timing and distributing devices.

5. In an ignition system for combustion engines, the combination with an engine having a plurality of cylinders; of an ignition system including a plurality of primary and secondary circuits; make and break devices for said primary circuit; a plurality of distributing devices for said secondary circuits; an engine driven shaft having provisions for actuating the make and break devices; a drive shaft actuated by said engine driven shaft to effectively operate the distributing devices alternately, whereby the secondary circuits will be selected in a recurrent sequence; and means associated with said engine driven shaft for making angular adjustments of said drive shaft relatively to said engine driven shaft.

6. In an ignition system for combustion engines, the combination with an engine having a plurality of cylinders; of an ignition system including a plurality of primary and secondary circuits; make and break devices for said primary circuits; a plurality of distributing devices for said secondary circuits; an engine driven shaft having provisions for actuating the make and break devices; a drive shaft actuated by said engine driven shaft to effectively operate the distributing devices alternately, whereby the secondary circuits will be selected in a recurrent sequence; and automatic means associated with said engine driven shaft for making angular adjustments of said drive shaft relatively to said engine driven shaft.

7. In an ignition system for combustion engines, the combination with an engine having a plurality of cylinders; of an ignition system including a plurality of primary and secondary circuits; make and break devices for said primary circuits; a plurality of distributing devices for said secondary circuits; an engine driven shaft having provisions for actuating the make and break devices; a second driven shaft actuated by said engine driven shaft to effectively operate the distributing devices alternately, whereby the secondary circuits will be selected in a recurrent sequence; and manual means and automatic means associated with said engine driven shaft for making angular adjustments of said drive shaft relatively to said engine driven shaft.

8. In an ignition system for combustion engines, the combination with an engine

having a plurality of cylinders; of an ignition system therefor, including spark timing and distributing devices; an engine driven member having driving connection 5 with the timing and distributing devices, and having provisions for driving the timing devices at one speed ratio and the distributing devices at a different speed ratio, relative to the speed of the engine driven 10 member; and manual means and automatic speed responsive means associated with said engine driven member for advancing or retarding the ignition timing and distributing means.

15 9. In an ignition system for combustion engines, the combination with a plurality of primary and secondary circuits; a timing device for said primary circuits; a distributing device for said secondary circuits; 20 means for driving the timing device and distributing device at different speeds; and automatic means for advancing or retarding the ignition timing and distributing means.

10. In an ignition system for combustion 25 engines, the combination with a plurality of primary and secondary circuits; a timing device for said primary circuit; a distributing device for said secondary circuits; means for driving the timing device and 30 distributing device at different speeds; and manual means and automatic speed responsive means for advancing or retarding the ignition timing and distributing means.

11. In an ignition system for combustion 35 engines, the combination with a plurality of primary and secondary circuits; a timing device for said primary circuits; a distributing device for said secondary circuits; means for driving the timing device and 40 distributing device at different speeds; and automatic speed responsive means for advancing or retarding the ignition timing and distributing means.

12. In an ignition system, the combination 45 with primary and secondary circuits, including terminals and spark plugs; of timing means for breaking and making the primary circuit, including an engine driven shaft; a plurality of distributing devices positioned 50 on the opposite sides of the timing means, said devices including a common operating shaft connected with said engine driven shaft; and automatic means associated with said engine driven shaft for advancing and 55 retarding the timing and distributing means.

13. In an ignition system, the combination 60 with primary and secondary circuits, including terminals and spark plugs; of timing means for breaking and making the primary circuit, including an engine driven shaft; a plurality of distributing devices positioned

on the opposite sides of the timing means, said devices including a common operating shaft connected with said engine driven shaft; and manual means and automatic 65 speed responsive means associated with said engine driven shaft for advancing and retarding the timing and distributing means.

14. In an ignition system, the combination with primary and secondary circuits, including terminals and spark plugs; of timing means for breaking and making the primary circuit; including an engine driven shaft; a plurality of distributing devices positioned on the opposite sides of the timing means, 70 said devices including a common operating shaft connected with said engine driven shaft; and automatic speed responsive means associated with said engine driven shaft for advancing and retarding the timing and 75 distributing means.

15. In an ignition system, the combination with an engine; of an ignition timing and distributing device including an engine driven shaft for controlling the timing of 80 the ignition, a shaft arranged at an angle to said engine driven shaft, gearing between said shafts, and automatic means on said first shaft for making angular adjustments 85 of said second shaft.

16. In an ignition system, the combination with an engine; of an ignition timing and distributing device including an engine driven shaft for controlling the timing of 90 the ignition, a shaft arranged at an angle to said engine driven shaft, gearing between said shafts, and manual means and automatic means on said first shaft for making angular 95 adjustments of said second shaft.

17. In an ignition system for internal- 100 combustion engines, the combination with a timing device and an engine driven member for operating the same; of a distributing device including a movable element, said timing and distributing devices being located 105 in separate stationary housings; a shaft carrying the movable element; gearing between the engine driven member and the shaft; and manually operable means and automatic means each for simultaneously 110 adjusting the operation of the timing and distributing devices with respect to the engine, and each of the said means being capable of making adjustments independently of the other, but effecting a joint control of the timing and distributing devices. 115

In testimony whereof I affix my signature.

CHARLES F. KETTERING.
